UNITED STATES PATENT OFFICE.

JOHN J. TONKIN, OF OSWEGO, NEW YORK, ASSIGNOR TO THOMSON KINGSFORD, OF SAME PLACE.

VALVE-MOTION FOR STEAM-PUMPS.

SPECIFICATION forming part of Letters Patent No. 414,956, dated November 12, 1889.

Application filed July 5, 1889. Serial No. 316,553. (No model.)

To all whom it may concern:

Be it known that I, JOHN J. TONKIN, of Oswego, in the county of Oswego, in the State of New York, have invented new and useful Improvements in Valve-Motions for Steam-Pumps, &c., of which the following, taken in connection with the accompanying drawings, is a full, clear, and exact description.

This invention pertains to the class of steam-pumps designated "direct-acting" pumps, and has especial reference to the valve-motion of the steam-engine of the pump.

The invention consists of a novel organization of a valve-motion which dispenses with the usual auxiliary piston, and comprises an oscillatory lever actuating the valve and having a limited gravitating play independent of the governing device which actuates the said lever, said gravitating motion imparting a quick motion to the valve when near the ends of its stroke, and thus admits steam into the cylinder in time to cushion the momentum of the piston at the end of its stroke and reverse the motion of the piston; and the invention also consists in certain peculiarities of the details of the aforesaid valve-motion and auxiliary devices employed in connection therewith, all as hereinabove fully described, and specifically set forth in the claims.

In the annexed drawings, Figure 1 is a side elevation of a steam-pump whose steam-cylinder is equipped with my improved valve-motion. Fig. 2 is an enlarged longitudinal section of said steam-cylinder and its steam-chest. Fig. 3 is a transverse section of the same on line $x-x$, Fig. 2; and Fig. 4 is a detached plan view of the valve.

Similar letters of reference indicate corresponding parts.

A represents the water-cylinder; B, the steam-cylinder; C, the piston of the latter cylinder, and C' the piston-rod, which is connected directly with the pump in the usual and well-known manner.

D denotes the steam-chest, and a the valve, which in this case is represented in the form of a reciprocating or so-called "slide" valve, but need not necessarily be of that character, inasmuch as my improved valve-motion

is adapted for oscillatory valves as well as slide-valves. Transversely through the steam-chest is extended a shaft c, which is suitably journaled in the sides of the steam-chest and is extended through one of said sides.

In the interior of the steam-chest are two arms b b, rigidly attached to the shaft c and having their ends entering between and engaging lugs d d on the valve a.

At the outside of the steam-chest is a lever L, which is rigidly attached at the center of its length to the shaft c, and in such a position as to cause its range of oscillation to be limited to inclinations equidistantly upward and downward from a horizontal position and cause its mean position to be horizontal. This lever I designate a "gravitating" lever for the following reasons: To this lever I connect a suitable weight o in such a manner as to allow said weight to travel in either direction from end to end of the lever, and consequently toward opposite sides of the fulcrum of the lever. Said lever and weight and their connection may be of any suitable form; but, in order to shield the weight and its track from dust and other interference with the movement of the weight, I prefer to form the lever of the tube and employ for the weight o a roller or ball, as illustrated in the annexed drawings.

I is a bifurcated lever, which is pivoted to the exterior of the cylinder beneath the lever L, and at a point in a vertical line drawn from the pivot of the lever L. The two prongs I' I' of the bifurcated end of the lever I terminate under the end portions of the lever L, equidistant from the pivot thereof, and between the ends of the said prongs and under side of the lever L is allowed a slight oscillatory play to the latter lever independent of the lever I, for the purpose hereinafter explained. To the piston-rod C' is attached the laterally-extending arm e, the free end of which is provided with an eye e', axially parallel with the piston-rod, and in the said eye slides the rod f, which is connected to the long arm of the bifurcated lever I. To the rod f are rigidly attached two tappets or nuts n n at such distances from opposite sides of the arm e as to cause the latter to come in

contact with said tappets alternately near the ends of the strokes of the piston-rod. Said contact causes the rod *f* to move with the piston sufficiently to swing the lever *I*, so as to cause one of its prongs *I'* to tilt the gravitating lever *L* into a reverse inclination, and this causes the weight or ball *o* to travel from one end to the opposite end of the lever *L*. The movement of the lever causes the arms *b b* to move the valve *a* so as to carry it out of communication with the steam-port of one end of the cylinder and into communication with that of the opposite end of the cylinder, and the latter portion of this movement is accelerated by the gravitation of the lever *L*, due to the weight *o* running to the lower end of said lever and imparting to the same a movement independent of the lever *I*, which movement is afforded by the play between the lever *L* and ends of the prongs *I' I'* of the lever *I*, as hereinbefore described.

It is obvious that my improved valve-motion is adapted to be used on engines operated either by steam, air, or water; hence by designating the cylinder *B* a "steam-cylinder" I do not wish it to be inferred that I limit myself to the use of my valve-motion solely to steam-cylinders.

Having described my invention, what I claim as new, and desire to secure by Letters Patent, is—

1. In combination with the piston-rod, steam-chest, and valve in said steam-chest, a governing-lever actuated by a piston-rod, a gravitating lever transmitting motion from the governing-lever to the valve and having a limited lost motion, and a weight adapted to travel on said gravitating lever lengthwise thereof and past its fulcrum, substantially as set forth.

2. In combination with the valve and governing-lever actuated by the piston-rod, an oscillatory tubular lever partaking motion from said governing-lever and having its range of motion limited to inclinations equi-

distantly upward and downward from a horizontal position, and actuating the valve, and a weight adapted to roll in said tubular lever lengthwise thereof, substantially as set forth.

3. In combination with the steam-chest, valve, and piston-rod, a shaft extending transversely through the steam-chest, an arm or arms secured to said shaft inside of the steam-chest and engaging the valve, a gravitating lever rigidly attached at the center of its length to the aforesaid shaft at the exterior of the steam-chest, a weight adapted to travel on said lever toward opposite sides of the fulcrum thereof, a shipper adapted to rock the gravitating lever, and a rod transmitting motion from the piston-rod to the shipper, substantially as specified.

4. In combination with the steam-chest, reciprocating valve, and piston-rod, lugs on the exterior of the valve, a shaft extending transversely through the steam-chest, arms rigidly attached to said shaft and engaging the aforesaid lugs, a gravitating lever rigidly attached at the center of its length to the aforesaid shaft outside of the steam-chest and disposed with its mean position horizontally, a weight carried on said lever and adapted to travel from end to end thereof, a bifurcated lever having its branches adapted to engage the aforesaid gravitating lever at opposite sides of its fulcrum, with a limited play between its points of engagement, an arm extending laterally from the piston-rod, a longitudinally-movable rod connected with the bifurcated lever, and tappets on the said rod in positions to come in contact with the arm of the piston-rod near the ends of the stroke of the latter, substantially as described and shown.

In testimony whereof I have hereunto signed my name this 25th day of June, 1889.

JOHN J. TONKIN. [L. S.]
